UNITED STATES PATENT OFFICE.

LAWRENCE E. BRANDON, OF DERBY, VERMONT, ASSIGNOR OF ONE-HALF TO HARVEY W. SILSBY, OF DERBY, VERMONT.

IGNITING DEVICE.

1,110,611.

Specification of Letters Patent. Patented Sept. 15, 1914.

Application filed October 16, 1913. Serial No. 795,542.

To all whom it may concern:

Be it known that I, LAWRENCE E. BRANDON, a citizen of the United States, residing at Derby, in the county of Orleans and State of Vermont, have invented certain new and useful Improvements in Igniting Devices; and I do hereby declare the following to be a full, clear, and exact description of the invention, such as will enable others skilled in the art to which it appertains to make and use the same.

The present invention relates to devices for igniting the carbon and oxygen gas inside the cylinders of internal combustion engines for the purpose of clearing the cylinders of such residual gases and carbon accumulations, and has for its purpose to provide a device of that character which may be readily carried about in the hand, and inserted and worked about in the engine cylinder as desired.

At the present time the cylinders of internal combustion engines are cleaned by the method of injecting the oxygen into the cylinders and igniting the same with matches or wax tapers, but this method is at fault in that the force of the gas blows out the matches or tapers, and there is the further disadvantage that a considerable quantity of the gas is lost. To overcome the foregoing mentioned disadvantages the present invention proposes to ignite the gas by electric sparking, the means for producing which is carried by the device.

With these and other objects in view the invention consists in the novel details of construction and combinations of parts more fully hereinafter disclosed and particularly pointed out in the claim.

In the accompanying drawings forming a part of this application, in which similar reference symbols indicate corresponding parts in the several views: Figure 1 illustrates the device partly in section and in diagram. Fig. 2 is a transverse sectional view taken on the line 2—2 of Fig. 1; and Fig. 3 is a similar view taken on the line 3—3 of Fig. 1.

Referring to the structure in further detail, 1 designates a tubular cylinder providing a handle and constructed preferably of fiber, or other insulated material, which is closed at one end by a cap 2 and is open

at its other end 3. A pair of relatively long strips of metal 4 and 5, providing conductors, are secured at one end to the cylinder 1 by means of screws 6, and the opposite ends 7 and 8 of said strips are spaced apart to provide a spark gap 9, as shown clearly in Fig. 1 of the drawing. A clip 10 is secured to the strip 5 adjacent the gap 9 by a screw 11, and has for its purpose to hold a wad of asbestos fiber which is adapted to be saturated with any inflammable fluid for a purpose presently to be explained.

The electrical apparatus for ignition consists of a series of batteries 13 connected by one wire 14 to the plug 15 secured to the cap 2, and from said plug the wire extends through an insulated covering 17 to one member of an ordinary circuit closing device 16 mounted on the handle. The other wire 18 connects with the primary 18^a of a transformer through the wire 19 and the interrupter 19^a, after the usual manner. The wire 19 is connected to the handle 1 through the plug 20, and has terminals 21 and 22 connected respectively to the circuit closer 16 and the inner end of the conductor strip 4. The secondary 23 of the transformer connects at one end to the wire 19, and at the other end with the wire 24 leading to the handle through the plug 25, and thence through the handle and connects at 26 with the inner end of the strip 5.

In the use of the device the members 4 and 5 are inserted in the cylinder and moved about to the different points where it is desired to ignite the oxygen and carbon, and then on pressing the push button of the circuit closer a continuous spark is obtained across the gap 9 sufficient to ignite the oxygen and carbon, and thereby burn out the carbon and clean the cylinder.

When it is desired to ignite small particles of carbon in the cylinder, the asbestos or other fiber 12 is saturated with gasoline and the igniter placed in the cylinder in contact with the carbon and oxygen, and on sparking the gasoline is ignited and the flame from the gasoline will burn away the small particles of carbon and oxygen gas, as will be clearly understood.

It is obvious that those skilled in the art may vary the details of construction and arrangement of parts without departing from

the spirit of my invention, and therefore I do not wish to be limited to such features except as may be required by the claim.

I claim:—

- 5 In an igniting apparatus, the combination of a handle; a pair of conductor strips mounted on said handle and spaced at one end to form a spark gap; means for closing and interrupting an electric circuit through
- 10 said conductor strips and causing sparking

at said gap; and a device carried by said strips for holding a saturated mass of absorbent material adapted to be ignited by the sparks, substantially as described.

In testimony whereof, I affix my signature, in presence of two witnesses.

LAWRENCE E. BRANDON.
